Specification for Design.

Patented Apr. 3, 1917.

Application filed February 9, 1917. Serial No. 147,725. Term of patent 14 years.

To all whom it may concern:

Be it known that I, GEORGE E. BALL, a citizen of the United States, residing at Stratford, in the county of Fairfield and State of Connecticut, have invented a new, original, and ornamental Design for a Platter, Tray, or Similar Article, of which the following is a specification, reference being had to the accompanying drawing, in which—

Figure 1 is a plan view of a platter embodying my new design;

Fig. 2 is a section taken on the line 2—2 in Fig. 1, and Fig. 3 is a transverse section taken on the line 3—3 in Fig. 1.

I claim:—

The ornamental design for a platter, tray or similar article, as shown.

GEORGE E. BALL.
